(57) **CLAIM**

The ornamental design for a entertainment center front, as shown and described.

DESCRIPTION

FIG. 1 is a left front perspective view of an entertainment center front showing my new design;

FIG. 2 is a front elevational view thereof; and,

FIG. 3 is a partial cross section taken from line 3—3 in FIG. 2, which is typical for moulding around the face thereof.

The views of the entertainment center front not shown form no part of the claimed design. The broken lines depicting hardware represent environmental elements only and form no part of the claimed design.
